WICKET GATE

John S. Carpenter, Orange, Mass., assignor to
Rodney Hunt Machine Company, Orange,
Mass., a corporation of Massachusetts

Application January 30, 1937, Serial No. 123,269

2 Claims. (Cl. 253—122)

This invention relates to a wicket gate for water wheel casings.

The principal objects of the invention are to provide a wicket gate capable of sealing the joint 5 against the next gate and prevent serious leakage at that point; to eliminate the difficulty of adjusting the individual wicket gates tight against leakage, after installation; to provide a compound flexible wicket gate having an appreciable amount 10 of spring so as to insure tightness of the joints without adjustment; to secure better efficiency due to the leakage of less water past the wicket gate, and to improve the conditions of manufacture and assembly so as to reduce cost.

15 Other objects and advantages of the invention will appear hereinafter.

Reference is to be had to the accompanying drawing, in which

Fig. 1 is a plan of a turbine water wheel casing illustrating a preferred embodiment of this invention and showing the wicket gate pins in section, and

Fig. 2 is an elevation of the same.

It has been customary to provide pivoted wicket gates around the casing, each of which comes into contact with the next one to close or control the openings between successive ones for the passage of water. This is the only joint or seal. There has always been serious leakage at these joints 25 in spite of various different types of adjusting means. Furthermore, it is difficult to adjust each wicket gate tight against leakage, especially after installation.

For the purpose of overcoming these difficulties 30 the wicket gates 10 usually formed of cast iron and pivoted on gate pins 11, are not made all in one piece but are provided with a plate 12 set into the cast iron wicket gate and formed of steel, bronze, or other material. The plate 12 is 35 formed with perforations 17. It is set into a mold and the metal poured to cast the rest of the wicket gate 10. The metal flows through the holes 17 and when it solidifies, leaves integral rivets to hold the plate solidly. The plates have 40 a degree of resiliency, so that when pressed

against the next wicket gate they will form a tight joint without adjustment, as indicated in dotted lines in Fig. 1.

The gate pin supports the wicket gate through a pair of bushings 13 at the top and bottom and the cast iron part of the wicket gate is hollow, being held together by an integral cast tie 14. Of course, the wicket gate is provided with a link hole 15 for receiving a pin on the operating link 16 according to the usual principle. 10

This composite flexible wicket gate has an appreciable spring temper so that the joints all around the casing are closed with great tightness. The yielding part is carried by and forms a part 15 of the wicket gate itself. This also provides a rather higher degree of efficiency due to the more favorable passage of the water and is manufactured and assembled less expensively and yet more efficiently than has been the case heretofore. No 20 adjustments have to be provided because, if they are not all exactly alike, the results are substantially the same, except that perhaps some of the joints are made under less pressure than others.

Having thus described my invention and the advantages thereof, I do not wish to be limited 25 to the details herein disclosed, otherwise than as set forth in the claims, but what I claim is:

1. As an article of manufacture, a wicket gate comprising a body of cast metal, a gate pin on which the said body is pivoted, and a central 30 tongue of spring metal projecting beyond the end of the gate proper and constituting an operating end of the wicket gate, for the purpose described.

2. In a turbine water wheel, the combination 35 of two circular series of gate pins, a cast iron wicket gate pivoted on one of each pair of pins, a metal spring plate cast into each wicket gate and projecting in the general direction of the wicket gate from the free end thereof and adapted 40 to engage the next wicket gate with yielding pressure in one position of the plate, and means connected with each of the pins of the other pair for swinging the gate.

JOHN S. CARPENTER. 45
